SOLDERS

Richard Chadwick, Birmingham, and William G. Heaton, Sutton Coldfield, England, assignors to Imperial Chemical Industries Limited, a corporation of Great Britain

No Drawing. Application September 7, 1950, Serial No. 182,660. In Great Britain November 16, 1949

2 Claims. (Cl. 75—175)

1

This invention relates to improved solders of the tin/zinc class containing a preponderating proportion of tin, for use particularly in soldering aluminum or aluminum base alloys.

Solders of this class have been known for many years and there has been a number of proposals for modifying them by the addition of various minor constituents such for example as aluminum, bismuth, lead, phosphorus, silver.

One of the major requirements in a solder is 10 good fluidity to enable uniform spreading and complete coverage of the surface to be bonded, and the object of this invention is to provide an improved solder having in particular a considerably improved degree of fluidity in comparison 15 with previously suggested solders of this class.

According to the present invention we provide a solder of the kind described containing 69.9 to 98.9% tin, 1 to 30% zinc, and 0.1 to 5% cerium.

In addition to the improved fluidity, the cerium 20 also exerts a beneficial effect on the corrosion resistance of the solder. If desired the solder may also contain 0.1-5% of aluminum for the purpose of further increasing its corrosion resistance. The cerium content may conveniently 25 be added in the form of misch metal. In the accompanying table there are given comparative corrosion and fluidity data for a series of alloys in accordance with the present invention and the corresponding basic alloys not containing cerium.

The corrosion results are expressed in terms of the time to failure, in hours, of soldered lap joints of aluminum in a salt spray cabinet, and

the fluidity readings are represented by the spread of a standard 1 gram sample of solder on a fluxed sheet of aluminum held at the stated temperature.

Table

Composition, Per Cent				Time to failure of lap joint in hours	Fluidity (spread of drop in mm.) at—		
Sn	Zn	Al	Ce		300° C.	350° C.	400° C.
95	5	—	—	450	13	36	45
94.5	5	—	0.5	550	26	44	78
90	10	—	—	200	14	36	48
89.5	10	—	0.5	400	28	45	81
88	10	—	2	500	30	52	90
80	20	—	—	1,050	13	31	42
79.5	20	—	0.5	1,300	27	42	75
78	20	—	2	1,400	31	50	84
75	25	—	—	1,400	—	25	36
74.5	25	—	0.5	1,550	—	36	52
88	10	2	—	650	18	36	47
87.5	10	2	0.5	750	25	39	67
86	10	2	2	850	29	50	78
78	20	2	—	1,650	17	34	45
77.5	20	2	0.5	1,800	27	46	68
76	20	2	2	1,950	—	54	80

We claim:

1. Solder containing 69.9-98.9% tin, 1-30% zinc, and 0.1-5% cerium.
2. Solder in accordance with claim 1, containing in addition 0.1-5% aluminium.

RICHARD CHADWICK.

WILLIAM G. HEATON.
